UNITED STATES PATENT OFFICE.

ALBERT L. BLACKMAN, OF NASHVILLE, ASSIGNOR OF ONE-FOURTH TO
E. F. FALCONNET, OF DAVIDSON COUNTY, TENNESSEE.

VESSEL FOR AERIAL NAVIGATION AND MACHINERY FOR PROPELLING THE SAME.

SPECIFICATION forming part of Letters Patent No. 250,417, dated December 6, 1881.

Application filed March 5, 1880. Renewed May 20, 1881. (No model.)

To all whom it may concern:

Be it known that I, ALBERT LIVINGSTON BLACKMAN, of Nashville, in the county of Davidson and State of Tennessee, have invented 5 certain new and useful Improvements in Vessels and Machinery for Handling and Propelling Vessels for Aerial Navigation; and I do hereby declare that the following is a full, clear, and exact description of the invention, which 10 will enable others skilled in the art to which it pertains to make and use the same, reference being had to the accompanying drawings, and to the letters of reference marked thereon, which form a part of this specification.

15 Figure 1 is a side elevation of an aerial vessel operated by one raising, lowering, and propelling screw on each side and a compound raising, lowering, steering, and propelling screw aft. Fig. 2 is a transverse section, showing the side screws in position for propelling. Fig. 3 is a longitudinal horizontal section of the same. Fig. 4 is a plan view of the actuating machinery for the same, showing the revolving cylinder carrying a motive shaft with 20 a universal joint and the combined steering movement. Fig. 5 is a longitudinal section of the revolving shaft, showing the loop-jaws, shifting bed K, motive-shaft O, universal joint, and propelling, steering, lowering, and raising 25 screw, with the reversing-gear. Fig. 6 is a transverse section of the same cut through the dotted lines z z, showing the epicycloidal reversing-gear. Fig. 7 is a longitudinal horizontal section of the revolving cylinder and loop-jaw, showing motive-shaft O, universal joint, rack on shifting bed K, shaft 2, and gear-wheel 30 1. Fig. 8 is a transverse section of the same cut through the dotted lines x x, showing the loop-jaws w w', shifting bed K, slot l, rack u, pinion 1, and end of propelling-shaft O. Fig. 35 9 is a transverse section of the same, taken through the dotted lines y y, showing the loop-jaws w w', shifting bed K, beveled gear-wheel 1, and journal-bearing i" for propelling-shaft. Fig. 10 is a plan view of the actuating machinery, showing the driving-shaft, revolving cylinders, driving pulleys and belts, universal 40 joints, and the machinery for changing or reversing the raising, lowering, steering, and propelling screws, also shown. Fig. 11 is a side ele-

vation of a shuttle-shaped aerial vessel, showing two screws on the side, a shifting steering, raising, lowering, and driving screw aft. Fig. 12 is a longitudinal horizontal section of the same, showing the gunwales, thwarts, actuating machinery and its connections, the shifting, lowering, raising, steering, and propelling screw aft, with its universal-joint connections, two sets of lowering, raising, and propelling side screws and connecting revolving cylinders, and the cross-girders. Fig. 13 is a side elevation of a shuttle-shaped aerial ship, showing a sheathed nose and a steering-screw forward. Fig. 14 is a longitudinal horizontal section of the same, showing the frame-work and 55 machinery as in Fig. 12, together with a steering, raising, and lowering screw forward with universal-joint connections. Fig. 15 is a transverse section of the vessel, showing the gallery, location of engine, gas-field, fire-proof division-walls, decks, &c., with the side screws. Fig. 16 is the stern of a rounded-end aerial vessel, showing a set of twin shifting lowering, raising, steering, and propelling screws. Fig. 17 is a longitudinal vertical section of the 60 vessel, showing, in partial perspective, the gunwales C, thwarts D, cross-girders e e, &c., curved frame J, cross-girders f f, &c., suspenders d d, &c., stanchions I I, &c., partitions k to gas-chambers, &c.

My invention relates to improvements in vessels for aerial navigation constructed of and on a light frame-work of wires, rods, thin metal tubing, or other suitable material, secured at the intersections, wholly covered with or 65 incased in silk, linen, thin metal, canvas, or other suitable material, made air and gas tight and fire and water proof by paint, varnish, or any compound in use, secured to the frame-work, presenting in form a cylinder with conoidal 70 ends, or the grayling fish, or a shuttle. The upper part or gas-field is divided into compartments and subdivided into chambers of suitable form and proper dimensions by partitions, is also made air and gas tight and fire-proof. 75 Each chamber is provided with an induct and educt pipe, automatic valves, and stop-cocks, and connected by a suitable device to a general exhaust-pipe. The lower part, or hull, is separated from the gas-field by a fire-proof 80

ceiling, and is divided into cabins cut into compartments, comprising the machinery, engine, and store rooms, coal-bunkers, gas-condensers, &c., all substantially stayed, strengthened, and supported by braces, cross-braces, suspenders, and supports of metal or any light material, and consists in revolving rotating screws on the sides secured to and revolved on cylinders working in journal-bearings on the interior of the vessel, a shifting, revolving and rotating, steering, raising, lowering, and propelling screw aft, a revolving and rotating, steering, lowering, and raising screw forward, all handled and worked by motive machinery inside of the vessel, a gallery around the sides, doors, windows, and ventilators in the shell and proper ground-tackle.

My invention also relates to improvements in machinery for raising, lowering, steering, and propelling aerial vessels, consisting of combined reciprocating and revolving cylindrical shafts and belt-sheaths provided with pulley-wheels, idlers, knotted or corrugated gear for endless chain-belt; beveled gear, adjusting-levers, endless belts, and general driving-shaft for handling and rotating the side screws; a reciprocating revolving cylindrical shaft provided with movable bearings, revolving shafts, and beveled gear for shifting the propelling, steering, raising, and lowering screw aft as well as the steering-screw forward, the whole connected by friction-clutches with the propelling-engine through one general driving-shaft, and all inside of the vessel proper.

Similar letters of reference indicate corresponding parts.

The dome-ridge A, preferably of tubing, forming an ellipsoidal curve or a plane, curved at the ends over from the stem to the stern of the vessel, secured at the ends in metal collars b b' is the main upper shaping-support of the vessel.

At a proper distance below the dome-ridge, running fore and aft, with its ends secured in the ridge A, is a cord, E, preferably of tubing. To the dome-ridge A and cord E the upper part of the gas-bags is made secure their entire length. At the foot of the dome-ridge A, running parallel with cord E, is a second cord, F, preferably of tubing, secured by the ends in the metal collars b b' at the nodes. The cord F is the base of the gas-field, the longitudinal support of the vessel, and the support for the ceiling of the cabin and the machinery used in handling the vessel.

Passing beneath the vessel's hull in an ellipsoidal curve from the metal collar b forward to the collar b' aft, in which it is secured by the ends, is a keelson, H, preferably of tubing, which gives form and strength to the vessel's keel. At a proper distance above the keelson, running parallel with cord F, is a third cord, G, preferably of tubing, with the ends secured fore and aft in the keelson H, to which it imparts strength, serving at the same time as a support for the store-room and cabin-floors and

ceiling for the engine and other compartments below.

Secured in a substantial manner to the dome-ridge at proper intervals from stem to stern of the vessel is a series of stanchions, I I I, &c., preferably of tubing, which, passing down through girders E, F, and G, where they are secured, take foot in and are firmly secured to the keelson H, thus uniting, strengthening, and supporting firmly in place the perpendicular frame-work of the vessel.

At right angles to the dome-ridge A, on a plane with cord F, both ends of each secured by the ends in the collars b b' at the nodes, are two corresponding ellipsoidally-curved gunwales, C C', preferably of tubing, which give breadth to the vessel. On the same plane, running within and parallel to the gunwales C C', are two other ellipsoidally-curved what may be called "thwarts," D D, preferably of tubing, secured by the ends to the cord F.

Intersecting and secured to the gunwales C C', thwarts D D, and cord F, at proper intervals from stem to stern, is a series of cross-girders, e e e e, &c., which maintain the vessel's beam, support from below the gas-bags and the cabin's fire-proof deck d', and sustain the actuating machinery.

Secured by the ends in and on the same plane with cord G, and running parallel with thwarts D D, is a second ellipsoidally-curved frame, J J, preferably of tubing supported from above by suspenders and stays d d d, &c. Secured by the ends in the frame J J, and passing through cord G, to which they are made fast, is a second series of cross-girders, f f f, &c., preferably of tubing, which form the support for the floor of the cabin and deck for the store-room, &c.

In addition to being the nodes for the stem and stern of the vessel, in which the general frame-work has footing, the metal collars b b' form the journal-bearings for the revolving shafts, which carry the steering, lowering, and raising screw forward and the propelling, steering, lowering, and raising screw aft.

h h' h² h³ are journal-bearings secured in the sides of the vessel, for the reciprocating revolving shafts which carry the side screws.

B B B are the gas-bags, filling the entire area on both sides of the stanchions I I, &c., between the vessel's ceiling d' and the dome-ridge A. These bags are constructed of silk, linen, thin metal, canvas, or any suitable strong light material, rendered air and gas tight and water and fire proof by paint, varnish, or other compound, and are subdivided into compartments and chambers by partitions k k k, &c., also made air and gas tight and fire-proof. These chambers are each provided with an automatic valve and stop-cock, and by an educt and induct pipe connected with the gas-condensers, and by stop-cock to a general waste-pipe. By this arrangement, in the event of one of the chambers leaking or there being too much or too little gas in it, the defect can

be readily remedied by either drawing off the gas for storing, permitting it to escape through the waste-pipes, or supplying a deficit from the gas-condenser.

5 By dividing the gas-bags into chambers the vessel is not left solely to the mercy of any one accident to the gas-bags, as an injury ordinarily cannot affect the entire supply of gas.

While the gas-bags may be constructed of the same material and of the same piece as the casing of the hull of the vessel, and otherwise lashed to the frame-work as herein pointed out, I prefer to make them separate and secure them in place by lashing them thoroughly 15 at the top to the dome-ridge A and cord E, and at the base to the gunwales C C, thwarts D D, cord F, stanchions I I, &c., and cross-girders c c c, &c., overlying, staying, and supporting the entire vessel by a substantial balloon-netting.

N N are screws of very large propulsive power, constructed of a light frame-work covered with some strong light material, placed, respectively, on the sides of the vessel. These 25 screws are designed to raise, to lower, or to propel the vessel. The description of one of these screws will serve for all. The hub of the screw terminates in a shaft, L, having journals n n' and flanges, shoulders, or collars j j. The 30 journals n n' take bearings and work in journal-boxings i i' within the revolving cylinder-shafts M M.

Secured on shafts L are vaults or pulley-wheels q, through which motion is conveyed 35 to the screw from a general driving-shaft, O, by means of an endless belt, p'. Screws O' and P, also of large propulsive power, constructed in the same manner as are the side screws, N N', are secured to and rotated by a revolving 40 shaft, O, broken by universal joints T, retained and operating in journal-bearings fixed in revolving cylinders M² M³, and in the shifting bed K, secured between upper and lower jaws, w w', which terminate the cylinders M² M³ at i².

45 Shifting bed K is a heavy metal ring or circle, with an axle boxing, i², through one face, and a horizontal slot, l, (long enough to permit the bed K to be moved and the motive-shaft to have free play,) in the opposite face, 50 and a corrugated or cogged rack, u, on one edge, the length of and immediately over slot l, in which the cogged wheel or pinion 1, carried on and by revolving shaft 2, operating within revolving cylinders M² M³, meshes.

55 Hollow sleeves, tubes, or cylinder-shafts M M' M² M³, which may be moved laterally by the aid of levers thereto respectively attached, revolve on their axes, as well in bearings in hangers secured to the frame-work within the 60 vessel as in bearings h h' h² h³ in the sides of the vessel and b b' in the bow and stern of the vessel. Cylinders M M' have idlers within and a beveled-gear band, m', surrounding their mouth; and axle boxings or bearings 65 i i' at the opposite end carry the side screws, N N', and act as sheaths for the endless pro-

pelling belts p', and by being revolved give new directions to the force of the side screws, N N', either to raise, lower, or propel the vessel. The lateral motion is given to loosen or 70 tighten the belts p'. The idlers inside are useful to prevent friction from or heating by the movement of the belt.

The gear-band m', meshing into the bevel-gear wheel m² on shaft m, is employed to revolve on their axes the cylinders M M'.

The revolving shaft O, to which screws O' and P are attached by universal joint T, is carried longitudinally through the vessel, passing through cylinders M² M³ and sleeves O³, and 80 forms the main driving-shaft of the vessel. This shaft has bearing's in the shifting bed K, cylinders M² M³, and in hangers secured to the frame-work within the vessel. The sleeve O³ is divided into sections, and serves as an axle for 85 the double-pulley wheels p p, which rest against shoulders 4 4', and are held in place by a movable toothed clutch, r r, adjusted to the main shaft O, as well as for the driving pulley wheels o o, which receive, through belts O² O², from 90 the driving belt wheels t t, connected with the motive-engine, the power and motion that actuate the entire machinery. The pulley-wheels o o are also secured on their axes by friction-clutches. These toothed or friction 95 clutches are handled by levers and govern the starting or stopping of the machinery. To be more explicit, I wish to say the sleeve or shaft O³ is divided into sections near each pulley thereon operating. The portion between the 100 driving-pulleys o o is separated in the center, and may revolve on shaft O without conveying motion to any other part of the vessel. Then by bringing into juxtaposition friction-clutch o', the screw, either fore or aft, may be rotated 105 through shaft O, and by coupling the toothed clutch r to the double pulley p or p, fore or aft, as the case may be, or to both, if desired, the pulley is secured in place and made to rotate with the shaft, carrying with it screws N N'. 110 It will thus be seen that either one or both of the end screws, or any set of the side screws, may be set in motion independent of any of the others; or all may be employed at one and the same time, if so desired.

115 On cylinders M² M³, near the end, within the vessel, is a bevel-gear band, o'' o'', that gears into a bevel gear wheel, s', fixed on the ends of shaft 5, which correspond to shafts m m, used for the purpose of revolving cylinders M² M³ 120 simultaneously on their axes when it is desired to change the direction of the action of the screws fore and aft. Within these cylinders each are two revolving shafts, O and 2. Shaft O passes down through the center of the cylinder and into universal joint T, and carries and conveys power and motion to the screw. Shaft 2 passes down through and near one side of the cylinder in proper journal-bearings, and carries at one end a gear-wheel, 1, used in moving the shifting bed K to the right or left when 125 it is desired to change the position or action 130

of the screw, and at the other end a small pinion or cogged wheel, s , which passes through a slot, v , in the cylinder $M^2 M^3$, meshing in a hoop, v' , spurred on the periphery v^2 and cogged on the inside v' .

3 is a chain-belt, carried around hoop v' and a corrugated pulley, (not shown,) by means of which hoop v' is revolved, carrying the pinion s , forming an epicycloidal wheel, by which the 10 shaft 2 is revolved on its axis, thereby changing the position of the shifting bed K without regard to the position of cylinder $M^2 M^3$. The combination and action of these wheels are more clearly shown in Fig. 6.

15 To give a clearer idea of the construction of the cylinders $M^2 M^3$ and the shafts therein working, I will describe one of them more fully.

Cylinder M^2 is a long metal tube or cylinder, of uniform diameter, terminating at the end 20 beyond the vessel in a loop or a double loop parallel to each other, with sufficient space between them to admit the shifting bed K, Figs. 5, 8, and 9. Within the cylinder are two sets of journal-bearings, one in the center, the other 25 near one side. In the set in the center the driving-shaft O rests and revolves. In the set near the side the shifting-shaft 2 rests and revolves. Shaft O is broken near the center of the loop by a universal joint, and continues out through 30 a journal-bearing, i' , Fig. 9, in the shifting bed K into the hub of the screw P, having passed through a slot, l , Fig. 8, in the opposite side. While in this position the screw operates directly astern. On the upper edge of the shifting bed K, over the slot, is a cogged rack or 35 beveled rack, which meshes with the wheel 1 on shaft 2. By revolving shaft 2 by the chain-belt 3 through cog-wheel s , gear-wheel 1 carries the shifting bed K around its own axis 40 until journal-bearing i' and the screw are carried to the side of the cylinder. Then by revolving the cylinder on its own axis the screw is carried up or down or from side to side, at the will 45 of the engineer. (See Fig. 5.)

W is the motive-engine, and communicates, 50 through band-wheels $t t$, endless belts $o^2 o^2$, and pulley-wheels $o o$, propulsive power to shaft O.

While describing a single screw fore and aft, I do not desire to confine my operations to one 55 screw, as shown in Fig. 16. I use, when the breadth of the vessel will admit of it, what I call "twin screws," operated and managed on the same general principle.

I want it distinctly understood that in the 60 construction of my vessel I make my gas-bags, vessel's hull, decks, ceilings, cabin-floor, and state-rooms fire-proof, and fit up, furnish, and provision my vessel as sea-going vessels are now provided with furniture, beds, bedding, &c. 65 When constructed as described and shown, I employ just sufficient gas to give the vessel equipoise while on the ground, and rely upon my screws for carrying the vessel upward and forward, and expect to control it in the air with the same facility with which vessels in the water are handled.

Having now fully described my invention, what I esteem as new, and desire to protect by Letters Patent, is—

1. A vessel for aerial navigation, consisting 70 of a hull and gas-field subdivided into compartments, the whole constructed within one shell, on one general frame, in the form of a shuttle or the salmon fish, provided with a shifting propelling, raising, lowering, and steering screw aft, and a shifting steering, raising, lowering, and propelling screw forward, attached respectively to revolving cylinders $M^2 M^3$, and each coupled by universal joints T to revolving shafts O, connected with the actuating machinery within the vessel, substantially as shown and described.

2. A vessel for aerial navigation, consisting 85 of a hull and gas-field subdivided into compartments, the whole constructed within one shell, on one general frame, in the form of a shuttle or the salmon fish, provided with a shifting propelling, raising, lowering, and steering screw aft, attached to revolving cylinder M^3 , and coupled by universal joint T to revolving shaft O, connected with the actuating machinery within the vessel, substantially as 90 shown and described.

3. A vessel for aerial navigation, consisting 95 of a hull and gas-field subdivided into compartments, the whole constructed within one shell, on one general frame, in the form of a shuttle or the salmon fish, provided with a shifting propelling, raising, lowering, and steering screw aft, a shifting steering, raising, lowering, and propelling screw forward, attached respectively to revolving cylinders $M^2 M^3$, and each coupled by universal joint T to revolving shaft O, and with raising, lowering, and propelling screws on the sides, secured to revolving cylinders $M M'$ from the interior, and all connected with and propelled by actuating machinery within the vessel, substantially as 100 shown and described.

4. A vessel for aerial navigation, built on 110 one general frame and under one cover, provided with a shifting lowering, raising, steering, and propelling screw aft, a shifting steering, lowering, and raising screw forward connected by universal joints to and propelled by 115 revolving shafts from the inside of the vessel, which pass out fore and aft through revolving cylinders and take bearings in shifting beds located between circular jaws formed on the ends of the cylinders fore and aft of the vessel, 120 substantially as shown and described.

5. A vessel for aerial navigation, comprising 125 hull and gas-field subdivided into compartments, the whole constructed within one shell, on one general frame, and provided with twin shifting lowering, raising, steering, and propelling screws aft, attached respectively to revolving cylinders, and each coupled by universal joints to revolving shafts connected with the actuating machinery within the vessel, a 130 steering, lowering, and raising screw forward, and raising, lowering, and propelling screws

on the sides, all actuated by machinery within the vessel, substantially as shown and described.

6. An aerial vessel on one frame and one cover, made air and gas tight and fire and water proof, provided with a revolving cylinder, terminating in upper and lower circular jaws, grasping a shifting bed for carrying and changing the position of the after screw used for raising, lowering, steering, and propelling the vessel, substantially as shown and described.

7. An aerial vessel constructed on one frame and under one cover, made air and gas tight and fire and water proof, provided with revolving cylinders coming through from the inside fore and aft, and terminating circular jaws W W', for carrying shifting beds K for changing the positions of the raising, lowering, steering, and propelling screws located fore and aft of the vessel, substantially as shown and described.

8. Revolving cylinder-shafts M² M³, terminating at the outer ends in looped jaws, in which are secured the circular beds for changing the direction of the screws fore and aft, provided with journal-bearings, and carrying on the inside two revolving shafts, one for driving the propelling, steering, raising, and lowering screw, the other provided with a pinion at one end, which meshes in and rotates the circular beds K, and at the other a pinion or cogged wheel, which passes out through a slot in the cylinders and meshes in rotating band v', cogged on the inside and spurred on the periphery, in combination with circular beds K, substantially as shown and described.

9. Revolving cylinder-shafts M² M³, terminating in the outer ends in looped jaws, and provided with a rotating band, v', spurred on the periphery and cogged or corrugated on the inner side of the circle, substantially as shown and described.

10. Revolving cylinder-shafts M² M³, terminating in looped jaws W W' at one end, having a slot, v, in the side near the other, provided with a rotating band, v', cogged on the inside and spurred on the periphery, in combination with an endless chain and corrugated pulley-wheel, for the purpose of revolving in its bearings shaft 2, provided with a pinion on the inner end, which meshes in the inner side of the band v', and a cogged wheel on the other, which meshes with and moves the shifting bed K, substantially as shown and described.

11. Revolving cylinder-shafts M² M³, terminating in looped jaws K, having secured on the opposite end a beveled-gear band, o'', in combination with a beveled-gear wheel, s', secured on shaft 5, for the purpose of revolving the cylinder-shafts on their respective axes simultaneously, substantially as shown and described.

12. In combination, revolving cylinders M M' and M' M³, bevel-gear bands, and beveled-gear wheels, for simultaneously revolving the cylinders, substantially as shown and described.

13. In combination, the revolving cylinders M² M³, terminating at one end in looped jaws w w', and provided with journal-bearings on the inside, the actuating-shaft O, shaft 2, and shifting bed K, substantially as shown and described.

14. In combination, the revolving cylinder-shafts M² M³, terminating at one end in loops w w', and provided with journal-bearings on the inside, the shifting bed K, rotating bands v', cogged on the inside and spurred on the periphery, shaft 2, and actuating-shaft O, substantially as shown and described.

15. In combination, revolving cylinder-shafts M² M³, terminating at one end in looped jaws, revolving shaft 2, having pinions at both ends and working in journal-bearings within the cylinders, rotating band v', cogged on the inside and spurred on the periphery, the endless chain-belt 3, and changing-bed K for changing the direction of the screws, substantially as shown and described.

16. In combination, revolving cylinder-shafts and circular bed K, the latter having a journal-bearing, i'', in one face, a slot, l, in the opposite, and provided with a cogged rack on the upper edge, substantially as shown and described.

17. In combination, revolving cylinder-shafts having corrugated or bevel-gear bands at one end, rotating band spurred on the periphery and cogged on the inner edge, endless chain-belt, cogged pinion s, passing through slot v, revolving shaft 2, carrying pinions at each end, circular bed K, revolving shaft O, universal joint T, and shifting, raising, lowering, steering, and propelling screws for vessels for aerial navigation, substantially as shown and described.

18. Revolving driving-shaft O, broken near the outer ends by universal joints T, incased part its length in segregated sleeves O³, on which are adjusted driving belt-pulleys o o and double belt-pulleys p p, secured in place thereon by toothed or friction clutches r r and fixed shoulders 4, in combination with a motive power for handling and propelling vessels for aerial navigation, substantially as shown and described.

19. Revolving driving-shaft O, broken near the outer ends by universal joints, incased part its length in movable segregated sleeves O³, in combination with friction or toothed clutches o' o' and driving belt-pulleys o o for conveying power, fixed shoulders 4 4, and friction or toothed clutches r r, for securing in place double belt-pulleys p p, through which power is communicated to belts p' p', substantially as shown and described.

20. Revolving driving-shaft O, as described, in combination with revolving cylinders M² M³, shifting bed K, and shifting, raising, lowering, steering, and propelling fore and aft screws O' P' for vessels for aerial navigation, substantially as shown and described.

21. Revolving driving-shaft O, broken near

- the outer ends by universal joints T, incased part its length in movable segregated sleeves O³, in combination with friction or toothed clutches o' o', driving belt-pulleys o o, fixed shoulders 4 4, double belt-pulleys p p, securing friction or toothed clutches r r, revolving cylinders M² M³, shifting beds K, raising, lowering, steering, and propelling fore and aft screws O' P, beveled gear u 1, pinion s, shaft 2, rotating band v', cogged on the inside and spurred on the periphery, and the endless chain-belt 3, for propelling and changing the course of vessels for aerial navigation, substantially as shown and described. 50
22. Revolving driving-shaft O, broken near the outer ends by universal joints T, incased part its length in movable segregated sleeves O³, in combination with toothed clutches o' o', driving belt-pulleys o o, fixed shoulders 4 4, toothed clutches r r, double belt-pulleys p p, endless belts p' p', vaults q q', and the raising, lowering, and propelling side screws for vessels for aerial navigation, substantially as shown and described. 55
23. Revolving side shafts, M M', provided with idlers within their mouths and friction bevel-gear bands m' without, and with journal-bearings i i' near the outer end, in combination with vaults q q', shafts L, screws N N', endless belts p' p', and double pulley-wheels p p, for handling vessels for aerial navigation, substantially as shown and described. 60
24. Revolving side shafts, M M', provided with idlers within their mouths and friction bevel-gear bands m' without, and with journal-bearings i i' near the outer ends, in combination with vaults q q', shafts L, screws N N', endless belts p', double pulley-wheels p, toothed clutch r r, fixed shoulder 4, movable segregated sleeve O³, revolving driving-shaft O, toothed clutches o' o', driving belt-pulleys o o, endless belt O², and band-wheels t t, connected with the motive-engine W, for handling and propelling vessels for aerial navigation, substantially as shown and described. 65
25. Revolving shaft O, segregated sleeves O³, driving-pulleys o o, double pulleys p, and friction-shoulders 4, in combination with toothed clutches o' o' and r r, substantially as shown and described. 70
26. Revolving shaft O, segregated sleeve O³, driving-pulleys o, double pulleys p, friction-shoulders 4, and toothed clutches o' and r, in combination with revolving cylinders M² M³, substantially as shown and described, 75
27. Revolving shaft O, segregated sleeve O³, driving-pulleys o, double pulleys p, friction-shoulders 4, toothed clutches o' and r, revolving cylinders M² M³, and universal joints T, substantially as shown and described. 80
28. Revolving shaft O, segregated sleeve O³, driving-pulleys o, double pulleys p, friction-shoulders 4, toothed clutches o' and r, revolving cylinders M² M³, universal joints T, and shifting bed K, in combination with raising, steering, propelling, and lowering screws fore and aft on vessels for aerial navigation, substantially as shown and described. 85
29. Revolving shaft O, segregated sleeve O³, driving-pulleys o, actuating belt-wheel t, belt o², double pulleys p, friction-shoulders 4, toothed clutches o' and r, endless driving-belt p', belt-sheaths and revolving cylinders M M', vaults q, journal-bearings u u', and side screws, N N', in combination with vessels for aerial navigation, substantially as shown and described. 90
30. In combination, bevel-gear bands m' on the ends of revolving cylinders M M', gear-wheels m², and revolving shafts m, for simultaneously revolving on their respective axes revolving cylinders M M' and changing the direction of the side screws, N N', substantially as shown and described. 95
- In testimony that I claim the foregoing as my own invention I affix my signature in presence of two witnesses.
- A. L. BLACKMAN.
- Witnesses:
- WM. P. YOUNG,
D. W. GLASSIE.
